UNITED STATES PATENT OFFICE.

OSCAR A. ALBRECHT, OF GRAND RAPIDS, MICHIGAN, ASSIGNOR TO O. A. ALBRECHT COMPANY, OF OMAHA, NEBRASKA, A CORPORATION OF NEBRASKA.

SHOE-LACE PACKAGE.

1,319,681.

Specification of Letters Patent.

Patented Oct. 28, 1919.

Application filed June 1, 1917. Serial No. 172,202.

To all whom it may concern:

Be it known that I, OSCAR A. ALBRECHT, a citizen of the United States, residing at Grand Rapids, county of Kent, and State 5 of Michigan, have invented certain new and useful Improvements in Shoe-Lace Packages, of which the following is a specification.

This invention relates to shoe lace packages.

My object is the provision of a simple, inexpensive, flat, compact, neat and secure shoe lace package, particularly adapted to tubular or round shoe laces, but not limited 15 thereto, wherein a pair of laces are applied to and wound on a backing in a novel manner, the ends of the laces being retained by the wound portion thereof and accidental loosening or unwinding being prevented.

20 The invention is set forth fully herein-after, recited in the appended claims, and shown in the accompanying drawings, in which:

Figure 1 is a front view;
25 Fig. 2 a rear view; and

Fig. 3 a section on line 3—3 Fig. 1.

The backing 1 of the package is of sheet material, preferably a piece of cardboard, or the like, having an aperture 2 preferably in 30 the location of the median line thereof, located considerably inwardly from one end of the backing 1. Near the other end of the backing is a second aperture 3 which is preferably disposed near the side edge of 35 the backing.

The ends of a pair of the tubular or other shoe laces are first drawn through the opening 3 and laid flat against the backing 1, in parallel arrangement, and allowed to extend 40 nearly to the opposite end of the backing parallel to and near a side edge thereof as shown at 4. The laces are then wound around the backing 1 and across the ends 4 as shown at 5 and the remaining end portions 45 6 are passed through the aperture 2 from the opposite side of the backing 1 to the direction in which the ends 4 are passed through the aperture 3 and are then tucked under the wound portion 5 in spread relation as 50 shown at 7. Preferably these end portions are crossed at 8 where they pass through the opening 2. The ends 6 are fully covered by the wound portion 5 at the back of the card or backing 1. The major portion of the 55 end portions 4 are covered by the wound

portion 5, but a sufficient portion thereof projects to display the tips or tags 9. Both end portions of the laces are anchored against accidental detachment and the entire package is neat, flat, and compact. Having no 60 specially formed packet, the package is inexpensively produced because the body or backing 1 comprises only a flat piece of cardboard or the like provided with two holes 2 and 3. On the space 10 of the backing 1 may be printed any desired matter to identify the shoe laces; the disposition of the ends 4 at one side of the backing 1 and the location of the aperture 2 considerably inwardly from the end of the backing leaves 70 the free space 10 for the aforesaid purpose. The space 11 at the lower end of the backing may also be utilized for printing, if desired.

Having thus described my invention, what 75 I claim as new and desire to secure by Letters Patent is—

1. A shoe lace package, comprising an elongated backing, and shoe laces, wound therearound, crosswise thereof in a single 80 layer, said laces having their end portions located between their wound portions and the backing and held thereby.

2. A shoe lace package, comprising an elongated backing, and a pair of shoe laces, 85 wound side by side in a single layer, around and crosswise of the backing, said laces having their end portions located between and crosswise of their wound portion and the backing on opposite sides of the latter 90 and held thereby.

3. A shoe lace package, comprising a backing having apertures at different points thereof, and shoe laces having their end portions protruding through the respective 95 apertures, said laces being wound in a single layer around said backing and said protruding ends, at right angles to said protruding ends.

4. A shoe lace package, comprising a back- 100 ing having apertures at different points thereof, and shoe laces having end portions passing through the respective apertures and protruding on opposite sides of said back- 105 ing, said laces being wound in a single layer around said backing and said protruding ends, at right angles to the protruding ends, one end portion of each place extending beyond the wound portion for the display thereof.

5. A shoe lace package or the like comprising an elongated backing having apertures at different points thereof, and shoe laces or the like wound crosswise around said backing and having their end portions passing through the respective apertures, and located between the wound portion and the backing on opposite sides of the backing, one end portion of the laces or the like 10 extending the full length transversely of the coils of the crosswise wound portions and projecting freely beyond the said crosswise wound portion for the display thereof, the

other end portion of the laces, or the like being wholly covered by the crosswise wound 15 portion.

6. A shoe lace package or the like comprising an elongated backing and shoe laces or the like crosswise wound thereon, one end portion of which projects freely beyond the 20 end of the crosswise wound portion for purposes of display.

In testimony whereof, I hereunto affix my signature.

OSCAR A. ALBRECHT.
